DESIGN FOR A BOTTLE CARRYING CASE

James Weiser Lehman, Atlanta, Ga., assignor to The Coca-Cola Company, Wilmington, Del., a corporation of Delaware

Application January 30, 1946, Serial No. 126,102

Term of patent 14 years

(Cl. D58—13)

To all whom it may concern:

Be it known that I, James Weiser Lehman, a citizen of the United States and resident of Atlanta, Fulton County, Georgia, have invented a new, original, and ornamental Design for a Bottle Carrying Case, of which the following is a specification, reference being had to the accompanying drawings, forming part thereof.

Fig. 1 is a top view of a bottle carrying case, showing my new design;

Fig. 2 is a bottom view;

Fig. 3 is a side view;

Fig. 4 is a cross sectional view of the side thereof taken along the line A—A of Fig. 1, looking in the direction of the arrows;

Fig. 5 is an end view; and

Fig. 6 is a cross sectional view of the end taken along the line B—B of Fig. 1, looking in the direction of the arrows.

I claim:

The ornamental design for a bottle carrying case, as shown.

JAMES WEISER LEHMAN.
